Primary Examiner — Keli L Hill*Assistant Examiner* — Sara S Sahneh(74) *Attorney, Agent, or Firm* — Samuel M. Korte; Max M. Ali(57) **CLAIM**

The ornamental design for a electronic device, as shown and described.

DESCRIPTION

FIG. 1 is a front perspective view of an electronic device according to the present invention;

FIG. 2 is a rear perspective view of the electronic device;

FIG. 3 is a top view of the electronic device;

FIG. 4 is a bottom view of the electronic device;

FIG. 5 is a front view of the electronic device;

FIG. 6 is a rear view of the electronic device;

FIG. 7 is a left side view of the electronic device; and,

FIG. 8 is a right side view of the electronic device.

The broken lines shown in the drawings represent portions of the electronic device that form no part of the claimed design.

1 Claim, 4 Drawing Sheets(56)
